(57) **CLAIM**

The ornamental design for vacuum lift for goods, as shown and described.

DESCRIPTION

FIG. 1 is a perspective view of a vacuum lift for goods;

FIG. 2 is a top plan view thereof;

FIG. 3 is a rear elevational view thereof;

FIG. 4 is a front elevational view thereof;

FIG. 5 is a right elevational view thereof;

FIG. 6 is a left elevational view thereof; and,

FIG. 7 is a bottom plan view thereof.

The broken lines in the figures show portions of the vacuum lift for goods which form no part of the claimed design.
